Primary Examiner — John Windmuller*Assistant Examiner* — Luqman McNeil(74) *Attorney, Agent, or Firm* — Middleton Reutlinger**(57) CLAIM**

The ornamental design for a control, as shown and described.

DESCRIPTION

FIG. 1 is an isometric view of the control showing our new design;

FIG. 2 is a front view of the design of FIG. 1;

FIG. 3 is a rear view of the design of FIG. 1;

FIG. 4 is a side view of the design of FIG. 1;

FIG. 5 is another side view of the design of FIG. 1;

FIG. 6 is a top view of the design of FIG. 1; and,

FIG. 7 is a bottom view of the design of FIG. 1.

The broken lines are included for the purpose of illustrating portions of the control that form no part of the claimed design.

1 Claim, 7 Drawing Sheets(56)
